UNITED STATES PATENT OFFICE.

HENRY W. ODLIN, OF EDGARTOWN, MASSACHUSETTS, ASSIGNOR, BY DIRECT AND MESNE ASSIGNMENTS, TO STROMBERG MOTOR DEVICES COMPANY, OF CHICAGO, ILLINOIS, A CORPORATION OF ILLINOIS.

CARBURETER.

1,321,073.

Specification of Letters Patent.

Patented Nov. 4, 1919.

Application filed June 4, 1914. Serial No. 842,890.

To all whom it may concern:

Be it known that I, HENRY W. ODLIN, a citizen of the United States, residing at Edgartown, in the county of Dukes and State 5 of Massachusetts, have invented certain new and useful Improvements in Carbureters, of which the following is a specification.

My invention relates to improvements in carbureters.

10 The invention aims to provide a carbureter having highly efficient means for maintaining constant the level of the liquid fuel in the reservoir, which supplies the same to the mixing chamber or spray nozzle therein; 15 to provide means whereby the liquid fuel contained within a storage tank arranged below the carbureter may be automatically fed to the reservoir or reservoirs by suction or partial vacuum created by the operation 20 of the engine, dispensing with the necessity of placing the liquid fuel in the storage tank under pressure exceeding atmospheric pressure; to provide means whereby different degrees of suction or partial vacuums are produced in the auxiliary reservoir and the mixing 25 chamber, whereby the apparatus will operate satisfactorily; and to provide apparatus of the above mentioned character which is simple in construction, inexpensive 30 to manufacture, compact, automatic in operation, and convenient in use.

Other objects and advantages of the invention will be apparent during the course of the following description.

35 In the accompanying drawings forming a part of this specification and in which like numerals are employed to designate like parts throughout the same,

Figure 1 is a central longitudinal sectional view through a carbureter embodying 40 my invention, and,

Fig. 2 is a similar view through a slightly different form of the invention.

In the drawings, wherein for the purpose 45 of illustration is shown a preferred embodiment of my invention, attention being called to Figs. 1 and 2, the numeral 5 designates an auxiliary reservoir or shell for holding liquid fuel such as gasolene or the like to 50 be mixed with or carburet the air. The numeral 6 designates a main reservoir, the same being preferably arranged below the auxiliary reservoir 5 in end-to-end relation, but not necessarily restricted to such ar-

rangement. In the present arrangement, the 55 lower end 7 of the auxiliary reservoir closes the upper end of the main reservoir 6, as shown.

Extending into the upper end of the auxiliary reservoir 5 is a liquid fuel supply 60 pipe 8, connected with a liquid fuel storage tank (not shown) which is arranged below the reservoirs 5 and 6. In the operation of my apparatus, the liquid fuel is supplied through the pipe 8 into the auxiliary reservoir 65 5, by suction or partial vacuum created within the auxiliary reservoir, without the aid of pressure exceeding atmospheric pressure upon the liquid fuel held within the storage tank.

70 Preferably arranged upon one side of the main reservoir 6 is a mixing chamber 9, formed in a conduit or shell 10. This conduit or shell is preferably cast integral with the main reservoir 6 but may be rigidly connected therewith by any suitable means. The conduit or shell 10 is preferably vertically arranged and is provided at its upper end with a flange 11, adapted for connection with the intake pipe or manifold of an internal combustion engine, not shown. The lower end of the conduit or shell 10 is formed open for the admission of air and a butterfly valve 12 is preferably arranged therein to regulate the passage of the air therein. 75 Arranged within the upper portion of the conduit or shell 10 is a second butterfly or throttle valve 13, for cutting off the supply of the gas or charge to the engine in accordance with the speed at which it is desired to 80 operate the engine. Above the valve 13 is an auxiliary air supply pipe 14, communicating with the conduit or shell 10 through ports 15. The supply of air through the pipe 14 is controlled by a shutter-valve 16. 85 In operation, the valves 12, 13, and 16 are all operatively connected whereby they are simultaneously operated by the throttle-lever, which in an automobile is ordinarily carried by the steering wheel.

100 Disposed between the upper end of the auxiliary reservoir 5 and the upper end of the conduit or shell 10 is a suction pipe 17, of relatively small diameter preferably having a bore of substantially one-eighth of an 105 inch in diameter, the same being provided with a check valve 18 opening toward the conduit or shell 10, whereby air may be

2
withdrawn or exhausted from the auxiliary reservoir 5 into the conduit or shell 10 but air or gas cannot pass in an opposite direction in this pipe 17. The function of having the pipe 17 of this small diameter is to provide means whereby the suction or partial vacuum within the auxiliary reservoir 5 is less than the suction or partial vacuum in the mixing chamber 9 for a purpose to be more fully explained. In operation, I have found that a suction or partial vacuum of about four pounds, more or less, is produced in the mixing chamber 9, while a suction or partial vacuum of about two pounds, more or less, is produced in the auxiliary reservoir 5. Extending longitudinally through the inner wall of the auxiliary reservoir 5 is a contracted port 19, preferably having a diameter of less than one-eighth of an inch, with its upper end in free communication with the upper end of the auxiliary reservoir 5 and its lower end in free communication with the main reservoir 6, whereby identical pressures are maintained within the two reservoirs, allowing the liquid fuel to readily flow from one to the other, as will be more fully explained.

Leading from the lower end of the main reservoir 6 is a liquid fuel outlet conduit 20, adapted to supply the fuel to a nozzle 21 which is provided with apertures 22, whereby the gasoline or the like may flow into the same. The upper end of the nozzle 21 is tapered and apertured at its reduced end, as shown. There is preferably a tapered pin or deflector 23, arranged in proximity to the apertured end of the nozzle 21, to aid in spraying the gasoline or the like. It is to be understood that I may employ any other form of spray device. -

The auxiliary reservoir 5 is provided preferably upon its upper end with an opening adapted to place the interior of the reservoir in communication with the atmosphere, the same being preferably in the form of a conduit 24, having its upper end open and beveled to provide a valve seat for an upwardly opening valve 25. The conduit 24 has communication with the interior of the auxiliary reservoir 5 through apertures 26. The valve 25 is rigidly mounted upon a reciprocating valve rod 27 operating within a stationary guide 28. Secured to the outer portion of the guide 28 is a horizontal arm 29, having a screw-threaded opening to receive an adjusting screw 30, the inner end of which is disposed in the path of travel of the outer end of the rod 27, to regulate the extent of outward movement of the rod and the valve 25 carried thereby. The rod 27 is moved by a reciprocating rod 31, also operating within the stationary guide 28. The rod 31 is rigidly connected with a float 32, operating within the auxiliary reservoir 5, as shown. It is thus seen that when the

level of the gasoline or the like within the auxiliary reservoir drops, float 32 descends, whereby valve 25 is seated. The suction from the engines creates a suction or partial vacuum within the conduit or shell 10, which produces a suction or partial vacuum through the means of pipe 17 in the auxiliary reservoir 5 whereby the liquid fuel is drawn up through the pipe 8 and discharged in the auxiliary reservoir. Upon the rise of the level of the liquid fuel within the auxiliary reservoir, beyond a predetermined point, float 32 is elevated to open or unseat the valve 25, thus placing the interior of the auxiliary reservoir in communication with the atmosphere, whereby the suction or partial vacuum is broken and the supply of gasoline cut off. The description thus far is common to both forms of the invention.

In Fig. 1, the numeral 33 designates a casting or housing preferably formed upon the end 7 of the auxiliary reservoir. The casting or housing 33 is provided with an axial opening or bore 34 having communication with laterally extending openings 35, which receive the liquid fuel from the interior of the auxiliary reservoir. The openings 35 are adapted to be covered and uncovered by a vertical reciprocating valve 36 secured to the float 32 to move therewith. Having communication with the lower end of the opening or bore 34 is a pipe or conduit 37, the lower end of which discharges into the lower end of the main reservoir 6, the same preferably having connection with a tubular coupling 38, extending into the main reservoir and provided with a valve seat 39. The numeral 40 designates a valve, or rod having a lower tapered end to engage and disengage the valve seat 39. The valve or rod 40, at its upper end, extends into the opening of the housing 33, which serves as a guide for the same. A screw-threaded plug 42 is arranged within the housing below and adjacent the upper end of the pipe 37, and a retractile coil spring 43 is confined between the plug 42 and the upper end of the valve or rod 40 and attached thereto to move the valve or rod 40 upwardly. The valve or rod 40 is provided below and adjacent the lower end of the casting or housing 33 with a ring or flange 44 rigidly connected therewith, which is engaged by cam heads 45 carried by levers 46, pivoted to the casting or housing 33 to swing in a vertical plane, as shown. The levers 46 are swung upwardly by engagement with a vertically movable float 47, provided with a central opening to receive the valve or rod 40, it being understood that this float is free to rise and fall independently of the valve or rod 40. It is thus seen that upon the supply of the gasoline or the like into the auxiliary reservoir 5 whereby float 32 rises and valve 36 is unseated, such gasoline passes through

the ports 35, opening 34, pipe 37 and through coupling 38 into the lower end of the main reservoir 6. This causes the float 47 to rise whereby levers 46 are swung upwardly, and valve 40 moved downwardly or seated when the level of the gasoline reaches its predetermined point.

In Fig. 2, different means are provided for supplying the gasoline or the like from the auxiliary reservoir 5 to the main reservoir 6. Such means comprises a casting or housing 48 provided with an axial opening or bore 49, having communication with the lower end of the auxiliary reservoir through ports 50 and with the upper end of the main reservoir 6 through ports 51, as shown. The ports 50 are adapted to be covered and uncovered by a vertical reciprocatory valve 52 secured to the float 32 to be moved thereby. The opening 49 is provided between its ends with a portion 53 serving as a valve seat, adapted for engagement with a vertically movable valve 54, to be unseated when moved upwardly. The valve 54 is rigidly connected with a reciprocatory rod 55, operating through an aperture in the lower end of the casting or housing 48. A compressible coil spring 56 surrounds the rod 55 and serves to move the valve 54 upwardly to unseat the same. The rod 55 is extended beyond the casting or housing 48 and is preferably enlarged, the lower end thereof operating within a stationary guide 57. The numeral 58 designates a float having a central opening to receive the rod 55, said float being adapted to rise and fall independently of the rod 55. Upon the upward movement of the float 58 the same moves levers 59 upwardly, said levers being provided at their upper end with cam heads 60, and pivoted to the housing or casting 48 at 61. The cam heads 60 engage a ring or flange 62 rigidly secured to the rod 55, whereby when the levers 59 are swung upwardly rod 55 is lowered and valve 54 seated. It is thus seen that when the level of liquid fuel rises in the auxiliary reservoir, elevating the float 32 and unseating the valve 52, valve 54 being open, such liquid fuel will pass through ports 50, opening 49 and through ports 51 into the main reservoir 6. Upon this supply of liquid fuel into the main reservoir 6, the float 58 thereof rises, swinging levers 59 upwardly, whereby the cam heads 60 will lower the rod 55 and return the valve 54 to its seat, when the level of liquid fuel within the main reservoir reaches the predetermined point.

The operation of the apparatus is as follows:

When the engine is operating, as is well known, a partial vacuum or suction is created in the inlet or manifold pipe of the engine, which is transmitted to the shell or conduit 10. This suction or partial vacuum

serves to draw air in through the shell or conduit 10, such air, when passing through the mixing chamber 9 taking up the sprayed gasoline or other liquid fuel, whereby the air becomes carbureted to form the charge. When this carbureted air passes the throttle valve 13, it is treated with a second supply of air, as is customary. A substantial suction or partial vacuum is also created within the upper end of the auxiliary reservoir 5, as the pipe 17 serves to establish communication between the auxiliary reservoir and the shell or conduit 10. This suction or partial vacuum draws the liquid fuel upwardly through the pipe 8 for automatically feeding the same into the auxiliary reservoir, such feeding of the liquid fuel being automatically controlled by the movement of the float actuated valve 25, which serves to make and break the suction or vacuum. This making or breaking of the suction or vacuum occurs upon the slight of perceptible change of the level of the liquid fuel, which is thereby maintained constant. Particular attention is called to the fact that by having the pipe 17 with a relatively small bore, the degree of suction or vacuum within the auxiliary reservoir 5 is far beneath the degree of vacuum or suction within the mixing chamber 9, whereby the higher degree of suction or vacuum within the mixing chamber 9 will serve to withdraw the liquid fuel through or from the spray device or nozzle 21 while this action will not be perceptibly opposed by the suction or vacuum within the upper end of the auxiliary reservoir. Particular attention is also called to the fact that the auxiliary reservoir and the main reservoir have independently operating float controlled means to maintain constant the level of the liquid fuel therein, whereby the level of the liquid fuel within the main reservoir 6 is maintained constant with a high degree of accuracy.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In combination, a carbureting passageway, a float chamber associated therewith, a fuel nozzle connected directly with said float chamber and disposed in said carbureting passageway, the level of fuel in said float chamber determining the head on said nozzle, an auxiliary chamber having a restricted connection with said passageway, a fuel supply leading to said auxiliary chamber, float valve mechanism for making and breaking the vacuum in said auxiliary chamber and

controlling the fuel outlet therefrom, a conduit directly connecting said auxiliary chamber and said float chamber, and float valve mechanism in said float chamber controlling said conduit.

2. In combination, a carbureting passageway, a float chamber associated therewith, a fuel nozzle connected directly with said float chamber and disposed in said carbureting passageway, the level of fuel in said float chamber determining the head on said nozzle, an auxiliary chamber superposed upon said float chamber and having a restricted connection with said passageway, a fuel supply leading to said auxiliary chamber, float valve mechanism for making and breaking the vacuum in said auxiliary chamber and controlling the fuel outlet therefrom, a conduit directly connecting said auxiliary chamber and said float chamber, and float valve mechanism in said float chamber controlling said conduit.

3. In combination, a carbureting passageway, a float chamber integrally formed therewith, a fuel nozzle connected directly with said float chamber and disposed in said carbureting passageway, the level of fuel in said float chamber determining the head on said nozzle, an auxiliary chamber superposed upon said float chamber and having a restricted connection with said passageway, a fuel supply leading to said auxiliary chamber, float valve mechanism for making and breaking the vacuum in said auxiliary chamber and controlling the fuel outlet therefrom, a conduit directly connecting said auxiliary chamber and said float chamber, and float valve mechanism in said float chamber controlling said conduit.

4. In combination, a carbureting passageway, a float chamber associated therewith, a fuel nozzle connected with said float chamber and disposed in said carbureting passageway, an auxiliary chamber having a restricted connection with said passageway, a fuel supply leading to said auxiliary chamber, float valve mechanism for making and

breaking the vacuum in said auxiliary chamber, a conduit directly connecting said auxiliary chamber and said float chamber, and float valve mechanism in said float chamber controlling said conduit, the two chambers being also connected by a restricted air connection.

5. In combination, a carbureting passageway, a float chamber associated therewith, a fuel nozzle connected directly with said float chamber and disposed in said carbureting passageway, the level of fuel in said float chamber determining the head on said nozzle, an auxiliary chamber having a restricted connection with said passageway, a fuel supply leading to said auxiliary chamber, float valve mechanism for making and breaking the vacuum in said auxiliary chamber and controlling the fuel outlet therefrom, a conduit leading through the bottom of said auxiliary chamber and directly connecting said auxiliary chamber and said float chamber, and float valve mechanism in said float chamber controlling said conduit.

6. In apparatus of the character described, an auxiliary reservoir provided at its lower end with a tubular housing, a main reservoir arranged near the auxiliary reservoir, a float operated valve arranged within the auxiliary reservoir to control the passage of liquid fuel into the tubular housing, a conduit connected with the tubular housing and discharging into the main reservoir, a valve having its lower end controlling the discharge of the liquid fuel from the conduit and its upper end operating within the lower end of the tubular housing, and float operated means arranged within the main reservoir and adapted to seat the second named valve upon its upward movement.

In testimony whereof I affix my signature in presence of two witnesses.

HENRY W. ODLIN.
